UNITED STATES PATENT OFFICE.

PHILIP JACOB MEAHL, OF SUMMIT, NEW JERSEY.

PERFORATING-MACHINE.

1,100,192.

Specification of Letters Patent. Patented June 16, 1914.

Application filed September 13, 1913. Serial No. 789,609.

To all whom it may concern:

Be it known that I, PHILIP J. MEAHL, a citizen of the United States, and resident of Summit, in the county of Union and State of New Jersey, have invented certain new and useful Improvements in Perforating-Machines, of which the following is a specification.

This invention relates to improvements in perforating machines and particularly to that class of perforating machines which are used for making perforated music sheets to be used in connection with automatically playing musical instruments, in which perforated music sheets the slots or perforations are arranged in a series of rows extending lengthwise of the sheet and spaced uniformly transversely to the sheet.

The object of my invention is to provide a new and improved perforating machine for the above-mentioned purposes, which is simple in construction, effective and reliable in action and by means of which perforations of different shapes, size, style or character can be produced successively or alternately in the same longitudinal row of slots or perforations all in a single passage of the blank sheet to be perforated through the machine.

In the accompanying drawings in which like letters of reference indicate like parts in all the figures: Figure 1 is a plan view of my perforating machine, parts being broken away and some omitted. Fig. 2 is a vertical longitudinal sectional view on the line *a—a*, parts being broken away.

The machine is constructed with a main frame 1 on which all the several parts are mounted. At the center of the main frame two standards 2 are provided, one on each side, in which is mounted the main drive shaft 3 carrying a fly wheel 4 and any suitable means for rotating the shaft from a source of power. On this shaft is fixed a cam disk 5 having a groove into which a pin 6 passes, which extends laterally from the top of a vertically reciprocating punch operating head 7 suitably guided in the side frames of the machine. Beneath the head 7 two transverse punch guides 8 are secured in the side frames, directly above two die-holding blocks 9 on the top of each of which a die plate 10 is secured. In the punch guide 8 a series of punches 11 are guided to move vertically, each punch being provided at its upper end with a button 12 which

rests in a recess 13 in the punch operating head 7, so that as the head moves upward the punches are all raised. Above each button 12 a horizontal punch controlling slide 14 is mounted on edge so that it can be shifted across the head 7 horizontally and each slide is provided in its bottom edge with a notch or recess 15 into which the button 12 of the punch directly below it can pass when said notch or recess is in alinement with the punch. In a bracket 16 at each end of the main frame 1, a transverse shaft 17 is mounted on which is secured a perforated master sheet drum 18 of conventional construction, which drum is provided at its end with sprocket teeth 19 which can pass in slots cut along the edge of the master sheet, in the well known manner. This drum is driven by suitable gearing to be described hereinafter, from the main shaft 3, so that a pre-determined relation is established between the speed of rotation of the main shaft 3 and the drum 18 and for each rotation of the main shaft, the master sheet drum is rotatively shifted a certain distance. A series of horizontal selector pins 22 are guided at their free ends by a guide plate 23 adjacent to and parallel with the drum 18 and the opposite end of each of these selector pins is pivotally connected with the upper end of a curved substantially L-shaped lifting lever 24 pivoted at 25 to a bar 26 having a series of vertical slots 27 in which said lifting levers 24 are severally located. Each selector pin is connected above its pivot with one end of a spring 28, the opposite end of which is secured to a bracket 29 on the bar 26, which springs serve to pull on the upper ends of the lifting levers, thereby gently pressing the free ends of the selector pins against the master sheet passing over the drum 18, the lower ends of which lifting levers each terminate in a head 30 resting within a notch 31 of a thrust block 32 of which one is provided for each lifting lever, said thrust blocks being suitably guided in slots in the bar 26 to move up and down vertically under the action of the lifting levers 24. Whenever a hole appears in the master sheet opposite the row of guide holes in the guide plate 23 the corresponding selector pin is forced to the right into said hole in the master sheet under the action of a spring 28 and thereby the corresponding thrust block 32 is raised as indicated in dotted lines.

A carriage 33, extending transversely across the machine frame is guided at its ends in a horizontal guide 34 so as to reciprocate horizontally and in said carriage one selector rod 35 is mounted for each slide 14 and corresponding lifting lever 24, one end of said selector rod being pivotedly connected with the corresponding slide 14 and the opposite end being connected with a U-shaped piece 36 mounted slidably in the carriage in such manner that the ends 37 of the long shanks of the several pieces 36 project beyond the right hand side of the carriage and into the paths of the several thrust blocks 32 whereas the shorter shanks of the U-shaped piece are each connected with one end of a spring 38, the opposite end of which is attached to the carriage, which springs thus serve for keeping the ends 37 of the U-shaped piece projected beyond the right hand side of the carriage and above the thrust blocks 32. The carriage 33 is provided with a laterally projecting pin 39 which is engaged by the lower forked end of a lever 40 pivoted at 41 and connected by a link 42 with a plate 43 having a longitudinal slot 44 through which the main shaft 3 passes. This plate carries a pin 45 which projects into a cam groove 46 of a cam disk 47 secured on the main shaft so that as the main shaft is rotated the lever 40 is rocked to and fro and correspondingly reciprocates the carriage 33 toward and from the thrust blocks 32.

The machinery just described is at the right hand end of the main frame 1 and identically the same machinery is found at the left hand end, but merely reversed so that each set of dies has its control slides, sliding carriage and selector pins and set of thrust blocks connected with the selector pins. The paper sheets 48 to be perforated are passed over the die plate 10 and this paper is shifted by a paper feeding device 49 of any well known construction. Adjacent to the outer edges and upper end parts of each group of lifting levers 24, at each end of the machine, I provide a bar 50 which can swing toward and from the upper parts of the lifting levers and serves as a restoring bar for bringing the lifting levers 24 and selector pins 22 connected therewith into normal position, once for each rotation of the main shaft. This bar 50 is connected by arms 51 at its end with a rock shaft 52 extending transversely across the machine, which rock shaft is operated by a bar 53 from a cam 54 of any suitable construction on the main shaft 3. A shaft 55 is driven by suitable gearing of any suitable kind from the main shaft 3 and I prefer to use for this purpose the Geneva star wheel so well known in machines of this kind, that it is not necessary to illustrate or describe it.

The shaft 55 at one end carries a bevel cog

wheel 56 engaging a bevel cog wheel 57 on a shaft 58 extending lengthwise of the machine and from which motion is transmitted by means of a worm 59 in the well known manner to one of the drive wheels of the paper feed mechanism, which paper feed mechanism and the means for operating it form no part of the present invention. At the opposite end the shaft 55 carries a bevel cog wheel 60 engaging two diametrically opposite pinions 61, each on a shaft 62 parallel with the sides of the machine, which shafts 62 each by means of a worm 63 drives one of the master sheet drum shafts 17.

70 represents a table which supports the paper passing over the die plates.

71 represents the master sheets.

The operation is as follows:—The master sheet must be so arranged that one master sheet controls the punches of one row of punches and the other master sheet controls the punches of the other row and the master sheets must be so arranged and spaced that the punches of each row of punches will be operated at the proper time. For example, if the right hand row of punches makes large holes, the left hand row of punches should make small holes, or holes of another shape. If in one of the longitudinal lines of perforations in the paper sheet there are to be three successive holes made by large punches and the last one of these is to be followed by nine successive individual punchings of small holes and the paper moves from right to left, the master sheets 100 are so arranged that the three successive large punchings are punched by one of the punches of the right hand group, the corresponding punch of the left hand group remains idle until finally the three holes made 105 by a punch in the right hand group have passed beyond the left hand group of punches whereupon the corresponding punch in the left hand group is operated the required number of times under control of the 110 corresponding master sheet. Whenever a hole in the master sheet comes in line with a corresponding hole in the plate 23 the corresponding lifting lever 24 raises its thrust block 32. The machine is so timed that the 115 passing of the selector pins into the master sheet and the lifting of the thrust blocks can only take place when the right hand carriage 33 has been moved to the left so that the projecting ends 37 of the U-shaped piece 120 36 are out of the way of the rising thrust block and when then the said right hand carriage moves to the right the ends 37 corresponding to the raised thrust blocks will strike against the raised thrust blocks, 125 whereby the ends 37 and the corresponding U-shaped parts 36, rods 35 and slides 14 are all pushed to the left so that the recesses 13 in the corresponding slides 14 are no longer over the punch buttons and consequently the 130

- corresponding punches are depressed when the punch head descends. For each rotation of the main shaft the paper is fed forward a predetermined distance, the punch head being raised. The carriages 33 are moved toward the center of the machine and at the same time the restoring bars 50 are swung from the lifting levers to permit some of the selector pins to pass through the holes in the master sheet whereby the corresponding thrust blocks are raised. Then the carriages 33 are moved toward the thrust blocks and the ends 37 encounter the front edges of the raised thrust blocks whereby the corresponding slides 14 are pushed toward the center of the machine and solid portions of the slides are above the corresponding punch buttons and then the punch head descends and forces those punches over which there are solid portions of the slides 14 through the paper. The punch head rises, the carriages 33 are moved toward the center of the machine again and the restoring bars 50 are swung toward the center of the machine thereby withdrawing the selector pins that have passed into the holes in the master sheet and bringing all the thrust blocks into normal position and so on for each rotation of the shaft.
- As has been pointed out, the corresponding punches in the two groups are in line so that one punch of each group can make a perforation in one and the same line or row of longitudinal rows of punchings in the sheet. The times at which the punches are depressed are controlled entirely by the arrangement of the slots in the master sheets and from the master sheet through the selector pins, lifting levers, thrust blocks, reciprocating carriages and the slides 14, the selection and operation of the punches are thus controlled.
- The master sheet drums 18 are provided with rows of holes as indicated on the right hand drum in Fig. 1 but the balance of these holes have been omitted to avoid confusion.
- Having described my invention what I claim as new and desire to secure by Letters Patent is:—
1. In a machine of the type described, the combination with a plurality of sets of punches and corresponding dies and means for operating them the perforations made by one set of punches differing from the perforations made by another set, of a plurality of sets of instrumentalities, one pertaining to each set of punches and controlling the operation of the punches of the respective set, said instrumentalities including a master sheet support and selector pins coöperating with a master sheet upon said support, the corresponding punches of the several sets being in line in the direction of the length of the machine, substantially as set forth.
2. In a machine of the type described, the combination with a paper feed mechanism for drawing paper through the machine in the direction of the length of the paper, of a plurality of sets of punches and corresponding dies and a common means for reciprocating the punches of all sets of punches the perforations made by one set of punches differing from the perforations made by another set, means for separately controlling the operation of each punch in each set, which means include a master sheet support and selector pins coöperating with the master sheet on said support, substantially as set forth. 70
3. In a machine of the type described, the combination with a paper feed mechanism for drawing paper to be perforated lengthwise of the paper through the machine, a plurality of sets of punches and dies pertaining thereto the perforations made by one set of punches differing from the perforations made by another set, means for reciprocating the punches, punch selectors pertaining to each set of punches, each set of punch selectors including a master sheet support, selector pins coöperating with a master sheet on said support and a single drive shaft and means on the same for operating all sets of punches and selector mechanisms from said shaft, substantially as set forth. 75
4. In a machine of the type described, the combination with a paper feed mechanism for drawing paper lengthwise through the machine, of a plurality of sets of punches and corresponding dies the perforations made by one set of punches differing from the perforations made by another set, a main shaft, a cam driven from the main shaft, a punch head operated from said cam for operating the punches, punch selecting means for each set of punches, said punch selecting means including a carriage, means for reciprocating the same from the main shaft, a group of thrust blocks, selector pins connected with the thrust blocks, a master sheet support coöperating with the selector pins and means for rotating the master sheet support from the main shaft, substantially as set forth. 80
5. In a machine of the type described, the combination with a paper feed mechanism for drawing paper lengthwise through the machine, of a plurality of sets of punches and corresponding dies the perforations made by one set of punches differing from the perforations made by another set, a main shaft, a cam driven from the main shaft, a punch head operated from said cam for operating the punches, punch selecting means for each set of punches, said punch selecting means including a carriage, means for reciprocating the same from the main shaft, a group of thrust blocks, selector pins connected with the thrust blocks, a master sheet support coöperating with the selector pins and means for rotating the master sheet support from the main shaft, substantially as set forth. 85
6. In a machine of the type described, the combination with a paper feed mechanism for drawing paper lengthwise through the machine, of a plurality of sets of punches and corresponding dies the perforations made by one set of punches differing from the perforations made by another set, a main shaft, a cam driven from the main shaft, a punch head operated from said cam for operating the punches, punch selecting means for each set of punches, said punch selecting means including a carriage, means for reciprocating the same from the main shaft, a group of thrust blocks, selector pins connected with the thrust blocks, a master sheet support coöperating with the selector pins and means for rotating the master sheet support from the main shaft, substantially as set forth. 90
7. In a machine of the type described, the combination with a paper feed mechanism for drawing paper lengthwise through the machine, of a plurality of sets of punches and corresponding dies the perforations made by one set of punches differing from the perforations made by another set, a main shaft, a cam driven from the main shaft, a punch head operated from said cam for operating the punches, punch selecting means for each set of punches, said punch selecting means including a carriage, means for reciprocating the same from the main shaft, a group of thrust blocks, selector pins connected with the thrust blocks, a master sheet support coöperating with the selector pins and means for rotating the master sheet support from the main shaft, substantially as set forth. 95
8. In a machine of the type described, the combination with a paper feed mechanism for drawing paper lengthwise through the machine, of a plurality of sets of punches and corresponding dies the perforations made by one set of punches differing from the perforations made by another set, a main shaft, a cam driven from the main shaft, a punch head operated from said cam for operating the punches, punch selecting means for each set of punches, said punch selecting means including a carriage, means for reciprocating the same from the main shaft, a group of thrust blocks, selector pins connected with the thrust blocks, a master sheet support coöperating with the selector pins and means for rotating the master sheet support from the main shaft, substantially as set forth. 100
9. In a machine of the type described, the combination with a paper feed mechanism for drawing paper lengthwise through the machine, of a plurality of sets of punches and corresponding dies the perforations made by one set of punches differing from the perforations made by another set, a main shaft, a cam driven from the main shaft, a punch head operated from said cam for operating the punches, punch selecting means for each set of punches, said punch selecting means including a carriage, means for reciprocating the same from the main shaft, a group of thrust blocks, selector pins connected with the thrust blocks, a master sheet support coöperating with the selector pins and means for rotating the master sheet support from the main shaft, substantially as set forth. 105
10. In a machine of the type described, the combination with a paper feed mechanism for drawing paper lengthwise through the machine, of a plurality of sets of punches and corresponding dies the perforations made by one set of punches differing from the perforations made by another set, a main shaft, a cam driven from the main shaft, a punch head operated from said cam for operating the punches, punch selecting means for each set of punches, said punch selecting means including a carriage, means for reciprocating the same from the main shaft, a group of thrust blocks, selector pins connected with the thrust blocks, a master sheet support coöperating with the selector pins and means for rotating the master sheet support from the main shaft, substantially as set forth. 110
11. In a machine of the type described, the combination with a paper feed mechanism for drawing paper lengthwise through the machine, of a plurality of sets of punches and corresponding dies the perforations made by one set of punches differing from the perforations made by another set, a main shaft, a cam driven from the main shaft, a punch head operated from said cam for operating the punches, punch selecting means for each set of punches, said punch selecting means including a carriage, means for reciprocating the same from the main shaft, a group of thrust blocks, selector pins connected with the thrust blocks, a master sheet support coöperating with the selector pins and means for rotating the master sheet support from the main shaft, substantially as set forth. 115
12. In a machine of the type described, the combination with a paper feed mechanism for drawing paper lengthwise through the machine, of a plurality of sets of punches and corresponding dies the perforations made by one set of punches differing from the perforations made by another set, a main shaft, a cam driven from the main shaft, a punch head operated from said cam for operating the punches, punch selecting means for each set of punches, said punch selecting means including a carriage, means for reciprocating the same from the main shaft, a group of thrust blocks, selector pins connected with the thrust blocks, a master sheet support coöperating with the selector pins and means for rotating the master sheet support from the main shaft, substantially as set forth. 120
13. In a machine of the type described, the combination with a paper feed mechanism for drawing paper lengthwise through the machine, of a plurality of sets of punches and corresponding dies the perforations made by one set of punches differing from the perforations made by another set, a main shaft, a cam driven from the main shaft, a punch head operated from said cam for operating the punches, punch selecting means for each set of punches, said punch selecting means including a carriage, means for reciprocating the same from the main shaft, a group of thrust blocks, selector pins connected with the thrust blocks, a master sheet support coöperating with the selector pins and means for rotating the master sheet support from the main shaft, substantially as set forth. 125
14. In a machine of the type described, the combination with a paper feed mechanism for drawing paper lengthwise through the machine, of a plurality of sets of punches and corresponding dies the perforations made by one set of punches differing from the perforations made by another set, a main shaft, a cam driven from the main shaft, a punch head operated from said cam for operating the punches, punch selecting means for each set of punches, said punch selecting means including a carriage, means for reciprocating the same from the main shaft, a group of thrust blocks, selector pins connected with the thrust blocks, a master sheet support coöperating with the selector pins and means for rotating the master sheet support from the main shaft, substantially as set forth. 130

pins connected with the thrust blocks, a master sheet support coöoperating with the selector pins and means for rotating the master sheet support from the main shaft 5 and a restoring bar for restoring all the parts of the selector mechanism back to normal position for each rotation of the main shaft, substantially as set forth.

6. In an apparatus of the type described, 10 the combination with a paper feed mechanism for drawing paper lengthwise through the machine, of a plurality of sets of punches and corresponding dies the perforations made by one set of punches differing from 15 the perforations made by another set, a main shaft for reciprocating the punches, a selector mechanism for each set of punches and means for operating both selector mechanisms from the main shaft, substantially as 20 set forth.

7. In a machine of the type described, the

combination with a paper feed mechanism, of a plurality of sets of punches the perforations made by one set of punches differing from the perforations made by another set, the punches in the several sets being arranged in parallel rows transversely to the paper and the punches of one set being in alinement with the punches of the other set in a direction lengthwise of the paper, a 30 selector mechanism for each set of punches and means for operating each selector mechanism once for each reciprocation of the punch operating means, substantially as set forth.

Signed at New York city in the county of New York and State of New York this 4th day of August A. D. 1913.
